UNITED STATES PATENT OFFICE

SIDNEY D. WELLS, OF QUINCY, ILLINOIS

PROCESS FOR DIGESTING FIBROUS MATERIAL

No Drawing.

Application filed July 11, 1925. Serial No. 42,978.

This invention relates to processes now in general use for removing from wood, straw, grass, bark and other fibrous plants, or portions thereof, the cellulose, ligno, pecto, cuto 5 or other forms or combinations of cellulose, for the purpose of using the same in the manufacture of paper pulp or other useful products, and comprises an improvement in the process disclosed in United States Patent No. 10 1,266,957 for Manufacture of wood pulp issued to myself and Otto Kress May 21, 1918.

More specifically, the invention relates to improvements in the so-called soda and sulphate and similar processes for doing this 15 work. In the customary processes for producing paper pulp from wood using alkalies or salts of the alkaline metals, the digesters are filled with wood chips and a volume of solution of the alkali sufficient to introduce the 20 required amount of the alkali and at the same time be sufficient in volume to provide proper distribution of the liquor by any of the means commonly employed such as centrifugal pumps, steam injectors, or rotation of the 25 digester on trunnions. The cooking operation is then commenced with a considerable volume of air in the digester which is removed so far as possible by relieving or blowing off steam from the digester while it is coming up to 30 pressure or after it has attained the desired pressure. Furthermore, at the commencement of the cooking operation, the liquor has not reached the interior of the chips and it is only after the outer portions of the chips 35 have been subjected to considerable digestion that the liquor comes in contact with the interior of the chips. It is well known that the influence of air on the cellulose content of the wood has a very deleterious effect on 40 the quality and yield of pulp obtained. Furthermore, the delay in the penetration of the chips by the cooking liquor brings about the over-cooking of the outer portions of the chips and by the time the liquor has reached the 45 inner portions, it has been very materially reduced in strength and activity so that the resulting pulp is composed of fibres cooked to widely different degrees.

The invention consists in a complete re-organization of the foregoing old processes by

which complete impregnation of the wood chips, or other material to be digested, takes place very early in the process; in which the presence of air in the digester is practically eliminated; and in which other improvements 55 hereafter more fully described occur, the whole resulting in great economies in the amount of chemicals required, the amount of fuel required and in the time of operating—these with increased yield of product and 60 improved product.

Stated in other words, some of the objects of the invention are: to remove the air from the digester before the cooking operation has started and thereby avoid the deleterious effect of the oxygen in the air in oxidizing the cellulose of the wood fibres which impair their strength and cause reduced yield of product; to save chemicals in cooking on account of the fact that the products of oxidation which 70 neutralize the alkalinity of the liquors are avoided; to produce a more uniform product with less chemical, and with a material saving in time on account of the greater uniformity of cooking and the smaller volumes of liquor 75 that may be used when the chips are thoroughly impregnated; to render greater concentration of the cooking chemical possible, whereby there is greater activity and smaller amounts of steam are required to heat the smaller volumes employed. 80

The invention further consists in many features and details hereafter more fully set forth.

In the process of this invention, any conventional form of digester, well known in the art, is provided and charged with the desired quantity of raw material to be digested. The digester is then completely filled with the liquor which is to act upon the material 85 to digest it. The digester is then closed and more liquor is added under pressure until the digester reaches a hydrostatic pressure of preferably in the neighborhood of 100# 90 per square inch—although the operation will take place from, say, 20# up. The digester is left in this condition for—at 100# pressure—about a half an hour, at the end of which time it is found that the material 95 to be digested, of ordinary commercial size,

is thoroughly impregnated with the digesting liquor, whereupon the digester is opened, say at the bottom, and enough of the liquor is withdrawn, preferably from the bottom and through a strainer, to reduce the quantity in the digester to that ordinarily used in cooking, say from one-third to two-thirds of the capacity of the digester not occupied by the material to be digested. During the withdrawal of the excess liquor, referred to, steam is admitted in sufficient quantity, preferably at the top of the digester to keep the digester full and prevent the entrance of air. The digester is then heated and the process carried on in the ordinary conventional manner to cook.

The great advantage of the invention is in replacing the liquor in the digester during impregnation by steam admitted above the liquor level and thereby preventing air to enter the digester. This must take place in all known processes if the liquor is to be removed without creating a vacuum, and thus preventing attainment of the desired effect on the product. The steps of this process can also be combined with a preliminary steaming before the liquor is introduced into the digester whereby a considerable amount of air is removed and a vacuum is formed in each chip as the cool liquor is run in, the result being that there is less air trapped in the chips to be removed later.

The alkalies or salts of alkaline metals referred to in the opening statement refer to compounds of the alkaline metals or earths such as the hydroxides, carbonates or bicarbonates, sulphides, sulphites, thiosulphates and similar sulphur compounds of the same and other compounds having an alkaline or reducing nature and exclude bisulphites or other compounds having an acid reaction which produce entirely different effects and are not included within the scope of this invention.

Having thus described my invention, what I claim as new and desire to secure by Letters Patent is:

1. In the art described, the method of placing a predetermined quantity of material to be digested in a closed digester, completely filling the digester with non-acid digesting liquor, allowing the filled digester to stand a sufficient length of time for the liquor to impregnate the material to be digested, then removing a portion of the liquor from the lower portions of the digester and simultaneously introducing steam to occupy the space vacated by the liquor whereby to prevent the formation of a vacuum in the digester and thus to exclude air from the material being digested, all this preparatory to heating the digester and thereafter proceeding in conventional manner.

2. In the art described, the method of placing a predetermined quantity of material to

be digested in a closed digester, completely filling the digester with non-acid digesting liquor to thereby exclude air from the digester, applying hydrostatic pressure to the contents of the digester, allowing the filled digester to stand a sufficient length of time for the liquor to impregnate the material to be digested, then withdrawing a quantity of the liquor from the lower portions of the digester and simultaneously introducing steam to occupy the space vacated by the liquor to thereby exclude air from the material being digested—this preparatory to heating the digester and proceeding in conventional manner.

3. In the art described, the method of placing a predetermined quantity of material to be digested in a closed digester, completely filling the digester with non-acid digesting liquor under hydrostatic pressure to thereby exclude air from the digester, thereafter allowing the filled digester to stand a sufficient length of time for the liquor to impregnate the material to be digested, then removing a quantity of the liquor from approximately the bottom of the digester and simultaneously introducing steam to occupy the space vacated by the liquor to thereby exclude air from the material being digested—this preparatory to heating the digester and proceeding in conventional manner.

4. The method of digesting fibrous material which consists in blanketing from the air a predetermined quantity of material to be digested by means of a nonacid liquor for a sufficient period of time to permit the liquor blanket to thoroughly impregnate the material to be digested, thereafter removing a portion of the liquor blanket and replacing same with steam in order to maintain exclusion of air from the material, thereafter proceeding in the conventional manner to cook the material.

5. In the process of digesting fibrous material, as a preliminary step the blanketing of a predetermined quantity of material to be digested in a closed container by completely filling the container with a suitable non-acid digesting liquor, permitting the filled digester to stand for a period of time sufficient to permit thorough impregnation of the material to be digested with the digesting liquor, thereafter removing a part of the digesting liquor from the digester while simultaneously introducing steam into the digester to occupy the space vacated by the removed liquor in order to maintain the inclusion of air from the digester and finally heating the digester and proceeding in the conventional manner.

In witness whereof, I have hereunto subscribed my name.

SIDNEY D. WELLS.
